UNITED STATES PATENT OFFICE.

WALTER T. CHARLES, OF CHICAGO, ILLINOIS.

FIRE-EXTINGUISHER.

1,256,874.

Specification of Letters Patent. Patented Feb. 19, 1918.

Application filed June 17, 1916. Serial No. 104,169.

To all whom it may concern:

Be it known that I, WALTER T. CHARLES, a citizen of the United States of America, and a resident of Chicago, county of Cook, 5 and State of Illinois, have invented certain new and useful Improvements in Fire-Extinguishers, of which the following is a specification.

The main objects of this invention are to 10 provide an improved form of liquid-discharging apparatus and particularly one which is adapted for use as a fire extinguisher; to provide improved means whereby the apparatus will discharge substantially all of its contents regardless of the 15 position in which it is held; and to provide an improved apparatus of this kind in which the liquid is discharged by a double acting pump located within the liquid-containing 20 casing.

An illustrative specific embodiment of this invention as applied to a fire extinguisher is shown in the accompanying drawings, in which—

25 Figure 1 is a longitudinal section of the fire extinguisher, the piston being in the position which it occupies during an upward stroke.

Fig. 2 is a detail showing the piston in a 30 position relative to its operating stem corresponding to a downward stroke.

Fig. 3 is an enlarged detail of the valve head and seat which close the discharge outlet when the device is not in use.

35 Fig. 4 is a perspective view of the air inlet pipe.

Fig. 5 is a detail of the inwardly facing flanges which are engaged by shoulders on the piston rod for locking the outlet closure.

40 In the construction shown in the drawings, an elongated tubular casing 1 is provided with caps 2 and 3, brazed on the opposite ends thereof to form a receptacle adapted to contain a fluid. The end 2 of 45 the receptacle is provided with a filler opening having a plug 4 threaded therein.

A pump cylinder 5 is rigidly mounted in the center of the receptacle 1 and is supported at its lower end by a tubular fitting 6 threaded therein. A piston 7 is slidably mounted in the pump cylinder 5 and is mounted on the lower end of a relatively large piston rod 8, the upper end of which is shaped to form a handle 9.

55 A suitable stuffing-box 10 is provided to prevent leakage between the piston rod 8

and the upper end of the pump cylinder 5, and a suitable stuffing-box 11 prevents leakage between the piston rod 8 and the cap 2.

In the specific form shown the piston rod 8 is tubular and the lower end is threaded to receive an end piece 12 on which the piston 7 is slidably mounted. The end piece 12 is provided with upper and lower stop shoulders 13 and 14 respectively for 65 limiting the sliding movement of the piston and is also provided with an elongated slot 15, the lower end of which is spaced slightly above the shoulder 14 and the upper end of which extends above and past the 70 shoulder 13.

The lower end 3 of the device is concave and has a discharge nozzle 16 passing therethrough and threaded into the tubular fitting 6 which supports the lower end of the 75 pump cylinder 5. The nozzle 16 has a central passage 17, the inner end of which is flared and the surrounding rim of which is shaped to form a valve seat 18.

The lower end of the pump cylinder is 80 closed by the fitting 6 which is provided with a central aperture through which extends a valve stem 19 having a valve head 20 at its lower end adapted to coact with the valve seat 18. Surrounding the stem 85 19 above the fitting 6 is a coiled compression spring 21 which bears against the fitting and a top part 22 on the valve stem, said compression spring being adapted to urge the valve head 20 away from the valve 90 seat 18.

The top 22 of the valve stem is located directly under the end 23 of the end-piece 12 and when the piston rod is thrust inward to its full limit the valve stem 19 is 95 forced downward, thereby seating the valve head 20.

Means are provided for locking the piston rod in its lowermost position and comprises a pair of inclined shoulders 24 formed 100 on the lower end of the end-piece 12 in position to wedgily engage the under side of the inwardly facing flanges 25 on the interior of the pump cylinder 5.

A valve casing 26 is rigidly mounted on 105 the pump cylinder 5 medially of its ends, and a pair of flexible discharge pipes 27 and 28 are provided each having one end mounted on and communicating with opposite ends respectively of said valve casing. 110 The other ends of said pipes are free and are surrounded by suitable weights 29 and

30 respectively for causing said ends to fall by gravity so that one or the other will reach the lowermost part of the receptacle regardless of the position in which 5 the fire extinguisher is held.

The valve casing 26 comprises a body part having a centrally located longitudinally disposed passage 31 surrounded at each end by protruding annular rims 32 and 10 33. The interior of the body part is cut away at each end and a pair of caps 34 and 35 to which the flexible discharge pipes are secured are slipped thereover, forming annular chambers of somewhat larger diameter 15 than the passage 31.

Means are provided for closing the ends of the passage 31 comprising a pair of cup-shaped valve heads 36 and 37 disposed with their open ends facing each other and connected together by a stem 38 which passes through and is considerably smaller than the passage 31. The flanges or rims of the cup-shaped valves 36 and 37 have sliding fit over the protruding annular rims 32 and 25 33, and are provided with ports 39 located so as to provide communication between the passage 31 and one or the other of the chambers at the ends thereof. The valve heads are slidable by gravity and being connected 30 by the stem 38 move as a unit so as to provide communication through the ports of one valve when shifted to a position to cut off communication through the ports in the other valve and vice versa.

35 Means for providing communication between the passage 31 and the lower end of the pump cylinder 5 are provided and comprise a pipe 40 disposed longitudinally of the pump cylinder and preferably diametrically opposite the valve casing 26. The lower end of the pipe 40 communicates with the interior of the pump cylinder 5 and the upper end is bent around the pump cylinder and is attached to and communicates with 40 45 the valve casing 26. A ball check valve 41 is provided for stopping any back flow of fluid.

The upper end of the pump cylinder 5 is provided with a discharge opening which 50 communicates with the tubular fitting 6 by means of a pipe 42 which is also preferably disposed along the pump cylinder diametrically opposite the valve casing 26.

Means are provided for introducing air 55 into the receptacle 1 as the liquid is pumped out, in order that a vacuum may not be formed in the casing, and comprise a small pipe 43 having one end which passes through the cap 2 so as to communicate with the atmosphere, said end being located so as to be covered by a downwardly flaring cap 44 secured to the piston rod 8. The pipe 43 leads down into the receptacle and is bent 60 so as to form a complete circle about the upper end of the receptacle, then continues 65

downward to the lower end of the receptacle, where it is similarly bent. This disposition of the air inlet pipe insures that whenever the outer end of said pipe 43 is below the level of the liquid in the casing there will be some part of said pipe which is above such liquid level and which will provide an air pocket preventing the escape of the liquid through said pipe prevents any siphoning of the liquid from the fire extinguisher. 70 75

In the operation of the apparatus the receptacle may be filled with fire extinguishing liquid through the filler opening, which has a removable plug 4. The piston rod is 80 initially thrust inward to its full limit and turned to the right, so that the inclined shoulders 24 wedgingly engage under the inwardly facing flanges 25. Thus the valve stem 19 is shifted downward against the action of the spring 21 so that the valve head 20 coats with the valve seat 18 and effectively prevents any escape of liquid from the apparatus. 85

When it is desired to use the apparatus 90 the handle 9 is turned to the left, thereby disengaging the shoulder 24 and allowing the spring 21 to raise the valve head 20 from the valve seat 18. The handle is then reciprocated in the usual manner of pumping. When the handle is pulled outward the piston 7 is engaged by the shoulder 14 of the end piece 12 and the movement of the piston then causes the fire extinguishing liquid to be drawn inward through the suction valve casing 26 and pipe 40. On the return stroke when the piston rod is thrust inwardly the piston 7 is engaged by the shoulder 13 as shown in Fig. 2, thus allowing liquid in the lower part of the cylinder 5 100 to pass into the elongated slot 15 and through the piston 7, the check valve 41 preventing back flow of the liquid into the receptacle 105. The piston rod 8, however, is of comparatively large diameter and consequently 110 displaces a considerable amount of liquid which has been drawn into the cylinder 5, said displaced liquid passing out through the pipe 42 and thence out of the opening 115 17 in the nozzle 16. When the piston is again drawn outward, the passage 15 is closed by the piston and the liquid in the pump cylinder 5 above the piston 7 is discharged through the pipe 42 as new liquid is drawn in behind the piston. 120

When the fire extinguisher is held in an upright position, as shown in Fig. 1 of the drawings, the cup-shaped valves 36 and 37 slide by gravity to the position shown, thereby closing communication through the upper suction pipe 27 and opening communication through the lower suction pipe 28. If, however, the fire extinguisher were to be inverted so that the liquid therein were to run to the opposite end of the casing, the 125 130

valves in the valve cylinder 26 would shift accordingly, closing communication with the upper pipe 28 and opening communication with the pipe 27.

5 The weights 29 and 30 on the free ends of the flexible discharge pipes cause said pipes to assume a lowermost position at all times in the casing, so that one of said ends will dip into the liquid at all times, regardless of the position in which the fire extinguisher is held.

On account of the pipe 43 being disposed peripherally around the interior of the casing at each end thereof, there will always be an air pocket at some point in the pipe, regardless of what position the device is held in, and consequently the break caused by such air pocket prevents the liquid from being siphoned out or otherwise escaping through the pipe 43.

Although but one specific embodiment of this invention is herein shown and described, it will be understood that numerous details of the construction shown may be altered or omitted without departing from the spirit of this invention as defined by the following claims.

I claim:—

1. An apparatus of the class described, comprising a receptacle for liquid, a double-acting force pump mounted in said receptacle, a valve casing mounted on said pump, a flexible pipe having one end communicating with said valve casing and having its other end freely movable within said receptacle, an intake pipe providing communication between said valve casing and one end of said pump, said pipe being located diametrically opposite said valve casing, a discharge nozzle and a pipe providing communication between said nozzle and the other end of said pump, said pipe being disposed diametrically opposite said valve casing.

5 2. An apparatus of the class described, comprising a receptacle for liquid, a pump cylinder mounted on said receptacle, a valve casing on said pump cylinder, a flexible pipe having one end communicating with said valve casing, a relatively large piston rod in said cylinder, a piston slidably mounted on the inner end of said rod, shoulders on said rod for limiting the sliding of said piston, said rod having a longitudinally disposed slot therein located in that part whereon said piston slides, and extending past one of said shoulders, said piston rod, slot, and piston being construct-

ed and arranged so as to provide communication from one side of said piston to the other side thereof when said piston rod is moved one way in said pump cylinder, and to close communication from one side of said piston to the other side thereof when said piston rod is moved the other way in said pump cylinder, said pump cylinder having an intake on said one side of said piston which communicates with said valve casing and an outlet on said other side of said piston, and a discharge nozzle communicating with the outlet of said pump cylinder, all being arranged to cause fluid to be positively forced out of said nozzle when said piston rod is moved one way, and to be forced out by the relatively large piston rod displacing the fluid when said rod is moved the other way.

3. An apparatus of the class described, comprising a receptacle for liquid, pumping mechanism for discharging the liquid from said receptacle, and an air inlet pipe having one end communicating with the atmosphere and the other end communicating with the interior of said receptacle, said air inlet pipe being coiled peripherally about the interior of said receptacle.

4. An apparatus of the class described, comprising a receptacle for liquid, pumping mechanism for discharging the liquid from said receptacle, and an air inlet pipe communicating with the outer air and with the interior of said receptacle at respectively opposite ends of said receptacle and being coiled peripherally about the interior of said receptacle.

5. An apparatus of the class described, comprising a receptacle for liquid, pumping mechanism for discharging the liquid from said receptacle, and an air inlet pipe having one end communicating with the atmosphere and the other end communicating with the interior of said receptacle, said air inlet pipe having communication with the atmosphere at the top of said receptacle and having a coil disposed peripherally about the interior of said receptacle at the top thereof, then extending downward and having another coil disposed peripherally about the interior of said receptacle at the bottom thereof.

Signed at Chicago this 18th day of June, 1916.
